UNITED STATES PATENT OFFICE.

OLAF J. ARNESS, OF MINNEAPOLIS, MINNESOTA.

SPRAYING ATTACHMENT.

Application filed August 1, 1921. Serial No. 488,903.

To all whom it may concern:

Be it known that I, OLAF J. ARNESS, a citizen of the United States, resident of Minneapolis, county of Hennepin, State of Minnesota, have invented certain new and useful Improvements in Spraying Attachments, of which the following is a specification.

The object of my invention is to provide a spraying attachment for use with a hose for spraying lawns, trees, shrubbery, golf putting greens, or wherever it may be desired to mix a chemical or other solution with the water.

10 A further object is to provide improved means for controlling the delivery of the chemical or solution to the stream of water.

Other objects of the invention will appear from the following detailed description.

20 The invention consists generally in various constructions and combinations, all as hereinafter described and particularly pointed out in the claims.

25 In the accompanying drawings forming part of this specification,

Figure 1 is a vertical sectional view through a sprayer attachment embodying my invention,

30 Figure 2 is a detail sectional view, showing the means for delivering the solution to the stream of water,

Figure 3 is a sectional view on the line 3-3 of Figure 2,

35 Figure 4 is a sectional view on the line 4-4 of Figure 2.

In the drawing, 2 represents a tank, preferably in the form of a cylinder, having a removable plug 3 for convenience in filling 40 the tank with the chemical or other material that is to be mixed with the stream of water. The filling opening is preferably located in one end of the tank and at the other end is a removable head plate 4 secured to an annular flange 5 by suitable means, such as bolts 6. When this plate is removed, an opening is exposed the full size of the tank. 7 is a water intake pipe leading into the tank near the plate 4 and provided with a cut-off valve 8 which, when closed, shuts off the flow of water through the tank. 9 is a similar pipe connected with the opposite wall of the tank, forming the exit for the stream of water and provided 55 with a controlling valve 8^a by means of which the discharge of water from the tank

may be prevented. To this pipe 9 the garden hose or pipe line is attached, having the usual nozzle for spraying purposes. This hose and nozzle I do not show in this application, as it forms no part of my present invention.

Within the cylinder 2 is a chamber 10 in which the chemical or other material is placed. 11 is a hollow piston rod mounted 65 at one end in a stuffing box 12 in the end wall of the tank and provided at its opposite end with a piston, consisting of discs 13 having packing rings 14 clamped between them to bear on the wall of the cylinder in the usual way. The end of the rod is exteriorly threaded, as indicated at 15. A spacing collar 16 is mounted on the rod between the discs 13 and nuts 17 are provided on each side of the discs for clamping them securely against the packing ring 14 and spacing collar 16.

The piston rod comprises an upper portion 18, preferably of tubing, and a lower section 19 having one end fitting the tubular part 18, and exteriorly threaded and provided with a longitudinal passage 20 communicating with lateral ports 21 which lead to the chamber 10 and similar ports 22 which communicate with the water chamber 23. 85 Between these ports on the threaded portion of the rod I provide the piston, as above described.

The part 19 in the piston rod is provided with a valve seat 29 and a valve 30 is mounted to slide in a guide 31 provided at the upper end of the rod section 19 and close communication between the passage 20 and the ports 21 above the piston. A rod 32 is connected at its lower end to the valve and has a threaded connection at its upper end with a plug 33 in the top of the tubular part 18, of the piston rod 11. A hand wheel 34 on the rod provides means for conveniently opening and closing the valve. A flange 35 90 limits the upward movement of the piston in the cylinder and a gauge bar 36 on the head of the cylinder provides means for indicating the position of the piston in the tank. 95

In the operation of the device, when water 105 is admitted to the chamber 23 and the valve 30 is opened, the pressure in the chamber 23 will raise the piston and a portion of the solution will be forced through the ports 21, the passage 20 and the ports 22 to mingle 110 with the stream of water flowing through the chamber 23. The volume of this delivery

may be regulated to a nicety by the adjustment of the valve 30 and the attendant by the movement of the wheel 34, can easily and quickly regulate the delivery of the chemical 5 or other material to the spraying stream. In this way a chemical may be automatically mixed with the stream of water for spraying lawns, trees, shrubbery, golf putting greens, and the like.

10 I claim as my invention:

1. A spraying attachment comprising a tank having at one end intake and discharge hose connections, a piston arranged in said tank, there being a water chamber 15 on one side of said piston communicating with said hose connections and a chamber for a chemical solution on the other side of said piston, a rod connected with said piston and having a passage therein extending on one side of said piston and ports communicating respectively with said chemical solution chamber and with said water chamber, a valve mounted in said passage between said ports for cutting off the flow of 20 the solution from one chamber to the other, and means extending to the outside of said tank for opening and closing said valve.

2. A spraying attachment comprising a tank having intake and discharge hose connections, a piston mounted in said tank and dividing the interior thereof into a chamber for a chemical solution, and a water chamber communicating with said hose connections, a rod for said piston comprising a 30 lower portion having a longitudinal passage therein extending above and below said piston and provided with ports communicating respectively with said chemical solution chamber and with said water chamber, the upper portion of said rod being 35 tubular in form and slidably mounted in one end of said tank, and a valve mounted in said tubular portion and adapted to close the passage in said rod between said ports,

upward movement of said piston when the 45 valve is open forcing the solution through the passage in said rod into said water chamber and said valve having a stem mounted in said tubular portion and an operating handle above said piston rod.

50 3. A spraying attachment comprising a tank having intake and discharge hose connections, a piston arranged in said tank, there being a water chamber on one side of said piston, communicating with said hose 55 connections, and a chamber for a chemical solution on the other side of said piston, a rod connected with said piston and having a passage therein communicating respectively with said chemical solution chamber 60 and with said water chamber, movement of said piston through the pressure in said water chamber forcing the chemical solution through said passage to mingle with the contents of said water chamber, and means for 65 regulating the flow of the chemical solution through said passage.

4. A spraying attachment comprising a tank having intake and discharge hose connections in its walls, a piston arranged in 70 said tank, there being a water chamber within said tank on one side of said piston communicating with said hose connections, and a chamber for a chemical solution on the 75 other side of said piston, said piston having a rod and a passage being provided leading from said chemical solution chamber to said water chamber, through which passage the chemical solution is forced to mingle with the contents of said water chamber when 80 said piston is moved by the pressure in said water chamber, and means for regulating the flow of the chemical solution through said passage.

In witness whereof, I have hereunto set 85 my hand this 27th day of July, 1921.

OLAF J. ARNESS.
